(57) **CLAIM**

The ornamental design for a hat with hat-band loops, as
shown and described.

DESCRIPTION

This application is co-pending with the following Utility
patent application: "Hat with Multi-Function Attachments",
application Ser. No. 15/871,796 filed by Zina Denny, et al.
on Jan. 15, 2018.

FIG. 1 is an isometric view of the front of the hat with
hat-band loops;

FIG. 2 is a front elevation view of the hat, the rear elevation
view is not shown as it is a mirror image of the front
elevation view;

FIG. 3 is a frontal view of the hat tilted downward;

FIG. 4 is a right side view of the hat tilted downward, the left
side view is not shown as it is a mirror image of the right side
view; and,

FIG. 5 is a top plan view of the hat, the bottom plan view is
not shown because it has no ornamental content.
